UNITED STATES PATENT OFFICE.

GEORGE M. BLACKWELL, OF DENVER, COLORADO, ASSIGNOR TO THE B AND G DISPLAY COMPANY, OF DENVER, COLORADO, A CORPORATION OF COLORADO.

DISPLAY ATTACHMENT FOR CANDY BOXES.

Application filed January 26, 1927. Serial No. 163,674.

This invention relates to improvements in display attachments for boxes for candy, cakes, crackers, tea, coffee, spices, dried fruits and other materials.

5 In the retailing of candies and other articles of merchandise that are made up into packages, it is desirable to have a sample of the contents on display so that the buyer can form an opinion of the quality and appearance of the goods.

10 In the retailing of candies, especially the cheaper grades thereof, it is a great convenience for the merchant to be able to prepare in advance, packages containing candy 15 of a given value so that when a sale is made he merely has to hand the buyer the required amount already done up in a package.

15 It is the object of this invention to produce an attachment that can be applied to the 20 open end of a paper caddy and which shall be provided with a glass covered box or compartment in which samples can be displayed and from which the glass cover can be removed only after the attachment has been 25 removed from the caddy.

The above and other objects that may become apparent as the description proceeds are attained by means of a construction that will now be described in detail, reference for 30 this purpose being had to the accompanying drawings in which the preferred embodiments thereof have been illustrated and in which:

Fig. 1 is a perspective view of a candy 35 caddy to the open end of which my attachment has been applied;

Fig. 2 is a section taken on line 2—2,

Fig. 1;

40 Fig. 3 is a section taken on line 3—3, Fig. 2;

Fig. 4 is a section taken on line 4—4, Fig. 1, in a plane at right angles to the plane of section 3;

Fig. 5 is a top plan view of a modified 45 form of construction;

Fig. 6 is a section taken on line 6—6, Fig. 5;

Fig. 7 is a top plan view of another embodiment of the invention;

50 Fig. 8 is a section taken on line 8—8, Fig. 7;

Fig. 9 is a section taken on line 9—9, Fig. 7;

55 Fig. 10 is a section similar to sections 6 and 8 and shows another modification; and

Fig. 11 is a section similar to that of Fig. 9 and illustrates a slight modification.

Numeral 1 indicates a pasteboard caddy of the type usually employed for transporting and storing candy. These caddies, as 60 a rule, have the upper edges of the side walls bent inwardly and downwardly in the manner indicated by numeral 2. A metal frame of U-shaped cross section, in which the sides have been designated by numerals 3 and 4 65 and the end or connecting portion by numeral 5, is made the same size and shape as the box and is attached to the latter by having the upper doubled over edge inserted between sides 3 and 4. A triangular box 70 having a bottom 6 and sides 7, 8 and 9 has the right angularly related sides 8 and 9 soldered to the sides 4 (Fig. 3). The upper edges of sides 8 and 9 are bent inwardly in the manner indicated by numeral 10 (Figs. 2 75 and 4) and a U-shaped member 11 is secured to the inner surface of the side 7 whose upper edge is bent inwardly so as to form a flange 12 that extends over the member 11.

A triangular piece of glass 13 has one edge 80 in the groove of the U-shaped member 11 and its other edges resting on the flanges 10. Along the upper edge of side 8 is a slot 14 and in line with this is a corresponding slot 15 formed in member 3. When the attachment is in place on the caddy, the upper edge of the latter will obstruct the passages between slots 14 and 15 and hold the glass 85 in place. When the glass is to be removed, the attachment is raised sufficient to permit 90 the glass to pass over the upper edge of the caddy.

In Figs. 1 to 4 a triangular box has been illustrated which is adapted to occupy a space in one corner of the caddy and this is 95 believed to be the preferable construction. In Figs. 5 and 6 there is illustrated an embodiment in which the box portion is rectangular. In other respects the construction is substantially the same as that above described. The glass 13^A can be removed through the slots 14 and 15, but is held in place by the upper edge of the caddy. In the two embodiments described above, the display box is soldered to the rectangular frame. It may be desirable, however, to make the frame comprising sides 3 and 4 as an independent structure to which the container is detachably connected and in Figs. 9, 10 and 11 such a construction is shown. 100 105 110

The container or box comprises the bottom 14', ends 15' and sides 16, which form a rectangular box to the upper edge of which has been soldered a finishing strip 17 that is 5 provided on three sides with downwardly extending flanges 18 whose inner surfaces are spaced from the outside of the box a sufficient distance for the rectangular frame to be received in this space. One of the 10 flanges 18 has a slot 15 through which the glass may be removed when the display compartment is raised a short distance.

The embodiment shown in Fig. 11 differs from that shown in Figs. 9 and 10 mainly 15 in this, that the flanges 18 are dispensed with and the glass 13^A can be withdrawn through a slot 19 in the rear wall. In this embodiment the rear wall of the box is provided with a strap 20 which has a hole for the reception of a fastener 21.

I desire to call particular attention at this point to one feature of the construction which is of great importance. The feature to which I refer and which greatly facilitates the application of the frame to the caddy has been clearly shown in Figs. 8, 9, 25 10 and 11 and consists in making the side 3 wider than the side 4. By this construction the frame can be put in place about the 30 caddy before the upper edge of the caddy is inserted between sides 4 and 3. It is evident that if sides 4 and 3 were of equal width the frame would be difficult to apply because the caddy would have to be inserted 35 in the space between sides 4 and 3 simultaneously with the application. In the drawing side 3 has been shown as the wider, but it is evident that the same advantages may be attained by making the side 4 the wider one 40 and it is therefore apparent that this advantage follows from having one side wider than the other. It will be observed that the several embodiments illustrated and described have this feature in common that 45 they all have a slidable glass top which can be removed through a slot in one of the side or end walls and which are secured to the upper edge of the caddy in such a way that the passageway through which the glass

must pass will be obstructed by the wall of 50 the caddy or metal rim on caddy.

The display attachments above described can be readily attached to the caddies and will give them a finished appearance. The samples can be conveniently put in place by 55 removing the glass and after the glass has been replaced they will be protected against dust and dirt and also against theft. These display devices will add greatly to the appearance of the caddies and the store room. 60

Having now described the invention what is claimed as new is:

1. A display attachment comprising a box having an open top, means forming a guideway along the upper edges of the sides, a 65 glass slidably supported in said guideways, one side of said box having a slot through which the glass may pass in being placed in position and removed, supporting flanges extending outwardly from some of the sides 70 and flanges extending downwardly from said supporting flanges, one of said downwardly extending flanges having a slot in line with the first mentioned slot.

2. A combined container and display device comprising, in combination, a caddy, a box having a sliding glass cover, one side of 75 said box having a slot through which the glass may be inserted and removed, and means for securing the box to the caddy in 80 such a position that the upper edge of the caddy will extend upwardly to a point above the slot whereby the glass will be held against removal.

3. A combined container and display device comprising, in combination, a caddy, a box having a sliding glass cover, one side of 85 said box having a slot through which the glass may be inserted and removed and downwardly extending flanges carried by 90 said box and spaced from its sides a sufficient distance to receive the upper edge of the caddy, one of said flanges having a slot 95 in line with the slot in the box, the space between said slots being obstructed when the box is in place on the caddy.

In testimony whereof I affix my signature.

GEORGE M. BLACKWELL.
